UNITED STATES PATENT OFFICE.

ARTHUR L. RUSSELL, OF BOSTON, MASSACHUSETTS, ASSIGNOR TO UNITED SHOE MACHINERY CORPORATION, OF PATERSON, NEW JERSEY, A CORPORATION OF NEW JERSEY.

STRETCHING APPARATUS.

1,346,258.

Specification of Letters Patent. Patented July 13, 1920.

Application filed February 11, 1918. Serial No. 216,481.

To all whom it may concern:

Be it known that I, ARTHUR L. RUSSELL, a citizen of the United States, residing at Boston, in the county of Suffolk and State of 5 Massachusetts, have invented certain Improvements in Stretching Apparatus, of which the following description, in connection with the accompanying drawings, is a specification, like reference characters on 10 the drawings indicating like parts in the several figures.

This invention relates to apparatus for stretching various sheet materials, as leather, and particularly to such apparatus for producing fullness in material over predetermined areas, as in the calf portion of blanks which are to be formed into leggings.

In work of this character, especially with certain grades of stock, the finished shape 20 of the article may be more readily and perfectly obtained by subjecting the blank, as a preliminary to the final forming, to a stretching operation over the portions of most abrupt curvature. The present invention 25 provides apparatus for this purpose, simple in construction and efficient in action, in which ample power is supplied for the stretching operation while permitting the area operated upon to be varied quickly to 30 give the shape sought.

A feature of the invention consist in a form having sections movable relatively to one another from a source of power to cause their successive separation and approach, 35 over which sections the material operated upon is placed to be stretched by the movement and to be shifted during such movement to vary its effect. In the illustrated embodiment of the invention, the form generally 40 resembles a portion of the surface over which the finished article is to fit, the sections being furnished by two similarly shaped, supplementary members having adjacent edges which recede from and approach one another under the influence of 45 the power drive. The work-engaging surfaces are inclined with respect to one another, diverging outwardly to opposite separated edges, said surfaces preferably being 50 curved.

As another feature of the invention, the engaging members are provided with means to prevent the work from slipping bodily over them during their recession. That this 55 retaining engagement with the work may not interfere with its ready positioning to

control the area operated upon, the retaining means coöperates with the hands of the operator, being here shown as furnished by the separated edges of the form over which the 60 material is bent and grasped by the operator. Material-engaging projections extending along these edges may also be provided, to aid in retaining in place the outer edges of 65 the stock during its stretching.

A further feature is found in means with which the stretching members are provided for extending the stretching action over the surfaces of the members. This means is 70 preferably applied near points at which the members separate to tension the material, and may consist conveniently of projections lying along the adjacent edges of the members to contact with the material over limited areas and raise it above the surfaces of 75 the members for some distance outwardly.

The above and other features are herein-after described in detail in connection with the accompanying drawings, in which,

Figure 1 is an end elevation of one form 80 which my apparatus may assume, parts being broken away, and

Fig. 2 is a section on the line 2—2 of Fig. 1, the housing and one of the stretching members being broken to show the operating 85 connections.

The main frame of the apparatus may be furnished by a housing 10 rising from a base 12 arranged for attachment to a bench or other support. The housing incloses the 90 motive elements of the apparatus and has at the top of the opposite side walls upward extensions 14, 14. These extensions carry stretching members which are movable relatively to one another. In Figs. 1 and 2 95 of the drawings, one member 16 is shown as integral with the extensions 14, while the other member 18 is pivoted upon the extensions to oscillate toward and from its companion, their upper work-engaging surfaces 100 20, 20 being inclined or diverging downwardly from adjacent meeting edges 22, 22 to opposite edges 24, 24. I prefer to have the stretching members furnished by similarly shaped sections of a contour generally 105 similar to a portion of the object over which the finished work is to fit. The apparatus here disclosed is adapted for stretching the calf portion of legging blanks, the form sections resembling the opposite vertical 110 halves of the rear calf portion of a leg, they being each curved transversely through

about 90° from the adjacent meeting edges to the opposite edges, the latter being separated by the transverse dimension of the calf. Longitudinally, or along their meeting edges, the members may also be leg-shaped, presenting a rather flat curved portion 26 falling off at 28 and 30 in the direction of the knee and ankle, respectively.

I have shown the form sections as consisting of hollow castings open at the bottom. The member 16 has vertical webs 32 continuing the frame extensions. In the extensions 14, 14, at their juncture with the webs 32, are horizontally-aligned, separable studs 33, 33 to enter openings in lugs 34, 34 near the ends of the form section 18. Pivoted upon opposite webs 36, 36 projecting into the interior of the sections are toggle links 38, 38, the central articulation of which is joined by a link 40 to a pin 42 of a crank disk 44. This disk is fixed to the end of a shaft 46 journaled in a bearing on the frame base and in one of the housing walls, and has fast upon it a pulley 48 through which the apparatus may be continuously driven from any suitable source of power to cause, by the straightening and breaking of the toggle, the form section 18 to move from and toward the section 16.

To retain the material to be operated upon in place on the form sections so that it may be stretched by their separation, the lower edges 24, 24 have means for resisting the bodily slipping of the material over the engaging surfaces 20 under the stretching tension. It is desired that this resistance to movement shall be attained while leaving the material free to be shifted readily for the presentation of new areas to be stretched.

To this end, the retaining means may be furnished in whole or in part by the depending edges 24 themselves, they giving longitudinally extending projections over which bights of the material S may be turned and grasped by the operator's hands, as illustrated in Fig. 1. A further retaining means is also shown in roughened surfaces at the outer lower portions of the engaging surfaces 20, there being series of projections 50, preferably pointed or V-shaped, with intermediate grooves lying parallel to the edges 24 of the sections. Against these projections the material may be forced by the hands of the operator, so that movement of its outer edges is resisted. It is to be noted that this retention of the material is not necessarily positive, but that it may slip to some extent and still be effectively stretched. In fact, by varying the firmness of his grasp upon the work, the operator may control the amount of fullness imparted.

In absence of means for distributing or extending the stretching action, there would be a tendency to somewhat sharply localize it between the points of maximum separa-

tion of the edges 22 of the members, this being due to the frictional engagement of the surfaces 20 with the material resisting stretching movement over them. To prevent this, I may provide some such means as projections 52, 52, preferably rounded at their extremities, extending outwardly along the edges 22. These projections act against the material by their smooth narrow surfaces, and therefore with slight frictional resistance, to raise it from the surfaces 20, as indicated at 5 in Fig. 1, and cause the stretching action of the movable sections to be effectively applied to these portions of the work over the form surfaces beyond the edges 22.

In using the apparatus of this invention for stretching the calf portion of legging blanks, the sheet S of legging material, properly tempered, is laid across the form sections, said material at each side extending below the section edges 24. When the edges 22 of the sections most closely approach one another, as the apparatus is continuously driven from the power-shaft 46, the material is grasped by the operator, who turns it under the edges 24 of the sections and forces it against the projections 50 to hold this portion of the material from slipping. The horizontal arrangement of the form renders this positioning of the material and its further manipulation easy. As the sections separate, that portion of the blank over and adjacent to the portion 26 of the form is stretched, the maximum effect being exerted between the edges 22, with a somewhat less action upon the material raised from the form by the projections 52 and a gradual diminution of stretching outwardly through the material which contacts with the surfaces 20. Longitudinally of the form, since the radial distance of the adjacent edges of the portions 26 from the axis of oscillation diminishes oppositely from their centers, the maximum movement of separation will be at said centers, and a corresponding stretching effect will be obtained. In this way the material is successively tensioned as a result of the alternate recessions and approaches of the sections. As the elasticity of the material lessens in stretching, the operator may take up the slack in the blank by drawing it more tightly over the form as the sections approach, or may shift it either laterally or longitudinally upon the form, each time grasping it anew to hold it against slipping. This continues until a sufficient fullness of the blank over the desired area has been obtained, when the stretched material is removed and the apparatus is ready for another operation.

Having thus described my invention, what I claim as new and desire to secure by Letters Patent of the United States is:

1. In a stretching apparatus, a form con-

sisting of a plurality of relatively movable sections over which the material to be stretched may be placed, and power-operated means arranged to cause successive separations and approaches of the sections to effect the stretching of each piece of work, the form being constructed and arranged to permit the material to be shifted over the sections during their successive movements.

10 2. In a stretching apparatus, a form consisting of a plurality of relatively movable sections over which the material to be stretched may be placed, and continuously operated means for effecting successive recessions and approaches of the sections.

15 3. In a stretching apparatus, two relatively movable stretching members associated to furnish a convex work-engaging surface, and continuously operating means for effecting successive recessions and approaches of the members to gradually stretch the work.

20 4. In a stretching apparatus, a form consisting of two similarly shaped relatively movable sections over which the material to be stretched may be placed, said sections having edges arranged to hold the work in stretching engagement under the influence of the hands of the operator, and power-operated means for separating the sections to effect the stretching.

25 5. In a stretching apparatus, a form consisting of a plurality of relatively movable sections over which the material to be stretched may be placed, the sections having portions arranged for such engagement with the material as to resist its slipping bodily upon said portions during the stretching operation, and power-operated means for moving the sections.

30 6. In a stretching apparatus, a form consisting of a plurality of relatively movable sections over which the material to be stretched may be placed, and means for effecting successive recessions and approaches of the sections, the form sections having portions arranged for such engagement with the material as to retard its slipping upon such portion during the recessions of the sections yet permitting said material to be shifted readily during the approach of the sections.

35 7. In a stretching apparatus, a form consisting of a plurality of relatively movable sections over which the material to be stretched may be placed, and means for separating the sections to effect the stretching, said sections having means for extending the stretching action over the surface of the form from the points of separation.

40 8. In a stretching apparatus, a form consisting of a plurality of relatively movable sections over which the material to be stretched may be placed, and means for separating the sections to effect the stretching, said sections having means to hold the ma-

terial away from the surface of the form adjacent to the meeting points of the sections.

45 9. In a stretching apparatus for legging material, a form provided with two relatively movable material-engaging surfaces generally similar in shape to a portion of a leg and in retaining engagement with which opposite edges of the legging material may respectively be placed, and power-operated means for separating the surfaces while the material is held in stretching engagement with both.

50 10. In a stretching apparatus for legging material, a form provided with two relatively movable material-engaging surfaces generally similar in shape to a portion of a leg and in contact with which the legging material may be placed, and continuously operating means for moving the sections toward and from one another, said sections being constructed and arranged to permit the material to be held in stretching engagement during their recession and to be shifted readily to present another area for stretching during approach.

55 11. In a stretching apparatus, relatively movable members having opposite separated edges arranged to engage the material to be stretched when this is pressed against them by the hands of the operator and resist its bodily movement under the stretching action.

60 12. In a stretching apparatus, a support for the material to be stretched consisting of relatively movable sections situated with edges adjacent one another while other edges of the respective sections are separated, said separated edges being arranged to engage the material turned over them to resist its movement when grasped by the operator.

65 13. In a stretching apparatus, relatively movable stretching members having work-engaging surfaces with adjacent edges, there being work-engaging projections extending beyond the work-engaging surfaces at the edges of the members.

70 14. In a stretching apparatus, relatively movable stretching members having work-engaging surfaces inclined to one another and converging to adjacent edges at which are work-engaging projections.

75 15. In a stretching apparatus, relatively movable stretching members having work-engaging surfaces inclined to one another and converging to adjacent edges at which are work-engaging projections, and means at the opposite edges to assist the operator to manually retain the work upon the members.

80 16. In a stretching apparatus, relatively movable stretching members having work-engaging surfaces inclined to one another and converging to adjacent edges at which are work-engaging projections, there being work-engaging means at the opposite edges of the members.

17. In a stretching apparatus, a form consisting of relatively movable work-engaging sections one of which is pivotally mounted, a power shaft, and connections from the power shaft to the pivoted member to oscillate said member to stretch the work.
18. In a stretching apparatus, a form consisting of relatively movable work-engaging sections one of which is pivotally mounted, a power shaft, a toggle connecting the sections, and a connection between the toggle and the power shaft.
19. In a stretching apparatus, a frame, a form section fixed upon the frame, a cooperating and similarly shaped form section pivoted on the frame, a toggle connecting the sections, a power shaft journaled in the frame, and connections between the power shaft and toggle.
20. In a stretching apparatus, a frame, relatively movable stretching members extending upwardly from the frame, said members having adjacent edges and being provided with work-engaging surfaces inclined outwardly and downwardly from said edges, a power shaft, and connections from the power shaft to the stretching members.
21. In a stretching apparatus, a frame, relatively movable stretching members extending from the frame, said members having adjacent edges and being provided with work-engaging surfaces curved outwardly from and along said edges, a power shaft, and connections from the power shaft to the stretching members.
22. In a stretching apparatus, a frame, and stretching members extending upwardly from the frame, said members having adjacent edges and being provided with work-engaging surfaces inclined outwardly and downwardly from said edges, there being upward projections above the work-engaging surfaces along the edges.
23. In a stretching apparatus, a frame, and stretching members extending upwardly from the frame, said members having adjacent edges and being provided with work-engaging surfaces inclined outwardly and downwardly from said edges, the opposite or lower edges being formed to resist bodily movement of the work under the stretching action.
24. In a stretching apparatus, relatively movable stretching members having work-engaging surfaces, there being projections from the members holding the work away over limited areas from the general work-engaging surfaces.
25. In a stretching apparatus, a support for the material to be stretched consisting of relatively movable sections situated with edges adjacent, there being projections extending along said adjacent edges.
26. In a stretching apparatus, a frame, and relatively movable stretching members extending upwardly from the frame, said members having adjacent edges and being provided with work-engaging surfaces inclined outwardly and downwardly from said edges, the opposite or lower portions of the members having work-engaging projections extending transversely to the direction of stretching movement.
27. In a stretching apparatus, a frame, stretching members extending upwardly from the frame, said members having adjacent edges and being provided with work-engaging surfaces inclined outwardly and downwardly from said edges, a plurality of work-engaging projections extending along the opposite or lower edges, a power shaft, and connections from the power shaft to the stretching members.
28. A form for stretching apparatus having supplementary sections arranged for relative oscillatory movement and being provided with work-engaging surfaces curved from adjacent edges in the direction of oscillation.
29. A form for stretching apparatus having supplementary sections arranged for relative oscillatory movement and being provided with work-engaging surfaces curved from adjacent edges in the direction of oscillation and also transversely thereto.
30. A form for a stretching apparatus having relatively movable sections provided with work-engaging surfaces inclined from adjacent edges at which edges are work-engaging projections.
31. A form for a stretching apparatus having relatively movable sections provided with work-engaging surfaces inclined from adjacent edges to opposite edges at which opposite edges are means tending to resist bodily movement of the work over the sections.
32. A form for a stretching apparatus having relatively movable sections provided with work-engaging surfaces inclined from adjacent edges to opposite edges along which opposite edges are a plurality of work-engaging projections.
33. A form for a stretching apparatus having sections relatively movable about an axis longitudinal of the form and provided with work-engaging surfaces situated at different radial distances from said axis.
34. In a stretching apparatus, a form consisting of a plurality of relatively movable sections over which the material to be stretched may be placed and automatic means for effecting repeated recessions and approaches of the sections.
- In testimony whereof I have signed my name to this specification.

ARTHUR L. RUSSELL.
